Attorney.

UNITED STATES PATENT OFFICE.

FRANK J. KRISTOFER, OF ST. PAUL, MINNESOTA, ASSIGNOR TO BROWN & BIGELOW, OF ST. PAUL, MINNESOTA, A CORPORATION OF MINNESOTA.

PENCIL.

1,360,230.

Specification of Letters Patent. Patented Nov. 23, 1920.

Application filed May 3, 1920. Serial No. 378,442.

To all whom it may concern:

Be it known that I, FRANK J. KRISTOFER, a citizen of the United States, residing at St. Paul, in the county of Ramsey and State 5 of Minnesota, have invented a new and useful Improvement in Pencils, of which the following is a specification.

This invention relates to improvement in pencils, the primary object of which is to 10 provide a simple structure for holding the propelling mechanism of the pencil in the casing or barrel, which incloses the same, so that the propelling means is firmly held for operation when in the barrel or can be removed to insert a new marking lead in the 15 socket of the propelling means.

It is also an object of this invention to provide means for frictionally engaging a portion of the propelling means to prevent 20 free rotation of the same when inclosed in the pencil casing. By means of this structure the lead propelling means is held against free rotation to prevent the lead held in marking position in the pencil from slipping. The frictional engagement of a portion 25 of the propelling means also prevents the operating head of the pencil from rotating too freely.

In the drawing forming part of this specification:

Figure 1 is a side elevation of the pencil.

Fig. 2 is a side elevation of the propelling means removed from the pencil casing.

Fig. 3 is a detail of a portion of the pencil.

Fig. 4 is an alternative construction of operating head for the pencil.

The drawings illustrate the pencil A with an outer barrel or casing 10, which is formed of hollow tubing, having its forward end 11 40 swaged to a conical shape, while the rear end 12 is formed with an opening to receive the lead propelling means of the pencil. The barrel 10 is formed cylindrical with a smooth inner contour from the rear end 12 45 to the conical end 11, and the apex 13 of the conical end 11 is provided with an axial opening which is approximately the same diameter as the marking lead used in the pencil.

50 The propelling mechanism B of the pencil A is formed with a threaded tubular member 14, which contains a longitudinally slotted tubular member 15, in which a driving member, having a socket 16, is adapted 55 to slide, the driving member being formed

with suitable means for engaging the inner surface of the threads 17 formed in the member 14, while the driving member is of ordinary construction. A suitable collar 18 is rigidly attached to the forward end of the 60 slotted tube 15, while a collar 19, having an operating head 20 formed thereon, is rigidly connected on the rear end of the member 15 so that the collars 18 and 19 form shoulders for the ends of the tubular member 14 to 65 hold the slotted tube 15 freely rotatable therein with the collars 18 and 19 rotatable at either end of the threaded member 14 but these members being held against longitudinal movement in relation to the threaded 70 member 14.

A spring sleeve 21 is rigidly secured at its forward end 22 by soldering, or any other suitable means, to the threaded member 14, while the rear portion thereof is flared outwardly to simulate a frusto-conical shape. Projecting from the rear edge 23 of the member 21 is a tongue 24, which is formed with a depressed portion 25. The tongue 24 extends over and is curved about a portion 80 of the collar 19 when the spring member 21 is rigidly attached to the member 14.

The threaded member 14, together with the collars 18 and 19, is slightly smaller in diameter than the inner diameter of the 85 barrel 10. Thus when the propelling mechanism B is inserted into the rear end 12 of the pencil A, the spring collar 21, which can be made of any suitable length, is adapted to engage a large portion of the inner surface 90 of the barrel 10 under spring tension so as to frictionally hold the portion 14 of the propelling means against rotation and longitudinal movement in the pencil barrel 10, but by exerting sufficient pull or force to 95 the head 20 of the propelling mechanism, the same can be removed from the barrel 10.

When the propelling mechanism is inserted in the barrel the spring sleeve 21 is contracted and the tongue 24, with the depressed portion 25, is brought into contact with the collar 19 to frictionally engage the collar so that when the operating head 20 is rotated to operate the propelling mechanism of the pencil the tongue 24 will engage 105 and hold the head 20 against free rotation and thus prevent the propelling mechanism from operating too freely. In this manner sufficient friction is provided to hold the operating mechanism in any position in 110

which it is set by the head 20 and to propel a marking lead 26 out of the apex 13 of the pencil. This spring tongue 24 is important in the construction of this pencil as it provides a simple, inexpensive means for holding the operating head and rotatable parts of the propelling mechanism B from free rotation so that when the pencil A is in use, pressure against the exposed end of the 10 marking lead 26 will not tend to operate the lead propelling means. The spring sleeve 21 also provides an inexpensive means for holding the mechanism or operating means in the pencil casing 10, while the casing 10 is 15 extremely simple, being formed of a thin tubing, the forward end of which is swaged into the desired shape with an opening in the apex for the marking lead. When the old marking lead is worn out, the propelling mechanism is removed and the stub remaining in the socket 16 of the marking lead is 20 removed, while a new marking lead is then inserted into the socket 16 and the propelling mechanism operated by the head 20 to 25 withdraw the marking lead into the propelling mechanism B, whereupon the mechanism B is then reinserted into the barrel 10 and the pencil is again ready for use.

The construction illustrated in Fig. 4 provides an operating head with a collar 19', which is similar to the collar 19, while the operating head 20' is formed with a holding ring 27 so that the pencil can be readily attached to a chain if it is so desired.

35 A feature of this invention is the simple, inexpensive construction and particularly that feature of the spring sleeve 21 and tongue 14.

In accordance with the patent statutes I 40 have described the principles of operation of my invention, together with the apparatus which I now consider to represent the best embodiment thereof, but I desire to have it understood that the construction shown is 45 only illustrative and that the invention can be carried out by other means and applied to uses other than those above set forth within the scope of the following claims:

I claim:

50 1. A pencil, including a tubular barrel, a propelling means and a spring sleeve secured to said propelling means adapted to be contracted by said barrel when said propelling means is inserted therein to hold said propelling means in said barrel.

2. A pencil, including a tubular barrel, a propelling means comprising relatively fixed and rotatable portions, a spring collar secured to the fixed portion of said propelling means and a tongue formed on said spring 60 collar adapted to engage the rotatable portion of said propelling means, whereby said spring collar and tongue are adapted to hold the fixed portion of said propelling means against longitudinal and rotary movement in 65 said barrel and said tongue is adapted to frictionally engage the rotatable portion of said propelling means, respectively, for the purposes specified.

3. A pencil, comprising a barrel, a propelling means comprising relatively fixed and rotatable portions and means adapted to frictionally hold the fixed portion of said propelling means against rotation in said barrel and to frictionally engage the rotatable portion of said propelling means to hold it against free movement when contained in 75 said barrel.

4. A pencil, comprising a tubular barrel, having a smooth inner contour of the same 80 inner shape as the outer shape of said barrel, a lead propelling means, including a threaded member and a relatively rotatable portion, means secured to said threaded member adapted to frictionally hold said 85 threaded member in said pencil barrel against longitudinal or rotary movement and means adapted to engage said rotatable portion of said propelling means to prevent free rotation of said rotatable portion. 90

5. A pencil, a barrel, a removable lead propelling means, said propelling means including a rotatable portion and a threaded portion and means adapted to hold said 95 threaded portion by friction against movement in said barrel and to simultaneously engage said rotatable portion of said propelling means to prevent free rotation thereof in the operation of said pencil.

6. A pencil, a barrel, a lead propelling 100 means comprising relative fixed and rotatable portions, means connected to said fixed portion of the propelling means adapted to hold the same against movement in said barrel and to simultaneously frictionally engage the rotatable portion of said propelling means to prevent free rotation of the same 105 in the operation of said pencil.

FRANK J. KRISTOFEK.
